CENTRIFUGAL SEPARATOR BOWL

Olof Einar Fröding, Stockholm, Sweden, assignor, by mesne assignments, to The De Laval Separator Company, New York, N. Y., a corporation of New Jersey

Application December 16, 1933, Serial No. 702,710. In Sweden January 18, 1933

4 Claims. (Cl. 233—20)

In an application filed by Henri Walch and Jean Prélaz May 11, 1931, Serial No. 536,500, there is set forth a centrifugal separator provided with three outlets, two of which are positioned, as in an ordinary centrifuge for separating two constituents of different specific gravities, comparatively close to, but at different distances from, the axis of rotation, while the third outlet (or series of outlets) is an outlet of capillary character in the peripheral part of the bowl wall. The bowl wall outlet functions to discharge one of the two heavier constituents. Where one of such two heavier constituents is free flowing and the other comparatively viscous, the former, whether heavier or lighter than the latter, will discharge through the bowl wall outlet. The provision of an outlet of capillary character may be, for example, by providing in the bowl wall a hole with an inwardly-opening frusto-conical valve seat and a valve extending into the hole and having a frusto-conical head which, by centrifugal force, is pressed outward to form a capillary throughflow channel between the valve and its seat for the escape of the heavy fluid constituent; or, as another example, it may be effected by a hole in the bowl wall having a countersunk recess and a headed pin which extends into the hole and has sleeved thereon ring-shaped discs or laminae which by centrifugal force are pressed together and against the base of the recess and afford between them capillary channels for the escape of the heavy fluid constituent.

Such a bowl is adapted, for example, for the separation of oil from the acid sludge formed in the treatment of lubricating oil with a mineral acid. Some of the acid is left in a free or uncombined state. It is desirable to separately discharge the oil (the lightest constituent) the acid sludge or goudron (the constituent of intermediate specific gravity) and the acid (which has the highest specific gravity). A bowl having the construction specified is adapted to continuously discharge the acid through the outlet of capillary character in the peripheral wall of the bowl, while the separated goudron, occupying a zone near the periphery, flows inward and discharges through the bowl neck.

The goudron, however, is not completely removed, but, owing to its consistency, a certain proportion remains in the bowl. It is important to promptly remove the same, since after it has had time to solidify in contact with the air, its removal is difficult.

The same condition may exist in the separation

of any three constituents, one of the two heavier of which is relatively viscous. It may exist where the bowl is provided with outlets for only two separated constituents, one of which outlets (or a series of which) is in the peripheral wall, if one of the heavy constituents is free flowing and the other heavy constituent is so viscous or semi-solid that it accumulates on the bowl wall, so as to necessitate stopping of the centrifuge preparatory to its removal.

The present invention is an improvement on the prior construction described in that it provides for the removal of the sludge or goudron through the bowl wall and specifically through an opening or channel that is normally closed during the separating action and may communicate with the orifice, beyond the capillary opening, through which the acid discharges during the separating action. The invention thus comprises a selective outlet or outlets which may be adjusted to allow, alternatively, the discharge of only one of the heavy constituents, and then the discharge of the other.

The drawing shows two preferred embodiments of the invention.

Fig. 1 is a sectional view through the peripheral wall of the bowl of one form of the selective outlet above generally described.

Fig. 2 is a similar view of another embodiment of the invention.

Referring first to the construction shown in Fig. 1: Into a threaded hole in the bowl wall *a*, which is preferably countersunk at its inner end, is screwed, from the inside, a headed screw plug *b*, the head of the plug confining tightly a sealing gasket *c* between it and the base of the countersink. Plug *b* is provided with a through axial hole *x*, into which extends a valve body *d*, of substantially smaller diameter than hole *x*, and provided with a frusto-conical head *e*, that engages a corresponding frusto-conical enlargement *f* of the inner end of hole *x*. The engagement between the conical head *e* of valve *d* and the conical seat at the inner end of the plug *b* should not be so tight as to seal the space between them, but a sufficient space, or sufficiently large channels, preferably of a capillary character, should be left between them to allow the escape, during the separating action, of the heavy free flowing constituent (e. g., sulfuric acid); but the space or channels must not be large enough to allow the escape of the relatively viscous, semi-solid heavy constituent (e. g., the goudron).

During the separating action the valve *d* occu-

pies the position shown in Fig. 1. After rotation of the bowl is stopped, the valve is moved and held inward so as to afford a sufficiently large (annular) opening to allow the escape of the contained heavy constituent (e. g., the goudron), that has accumulated in the bowl, when the bowl is again put into rotation. To allow valve *d* to be moved inward it is provided with a pin *g* which may be engaged with a spiral groove *h* in the inner wall of screw plug *b*. The outer end of plug *b* is provided with a cross-groove *k*, which may be engaged by a screw driver to enable the valve to be turned to move pin *g* into groove *h*, continued turning of the valve effecting its re-cession. At the end of the inward turning movement of valve *d*, pin *g* engages a depression *i* at the inner end of the groove. Valve *d* is thereby held in its inward position during the subsequent rotation of the bowl, preventing centrifugal force from moving the valve outward against its conical seat. When valve *d* is thus moved and held inward, a sufficiently capacious annular outlet is provided to allow the escape of the accumulated viscous liquid or semi-solids.

25. The described construction is but one of many different embodiments of the invention. The construction shown in Fig. 2 comprises an outer screw plug *m* threaded into an orifice in the bowl wall; an inner screw plug *n* threaded into the outer screw plug and provided with a frusto-conical head *o* engaging, preferably tightly, a corresponding recess on the inner end of plug *m*; and a nut *p* threaded on the inner end of plug *n* and confining between it and the head *o* ring discs or laminae *r*, preferably of etched sheet metal, affording between them capillary channels for flow of non-viscous heavy liquid. Plug *n* is provided with a central bore *s* and with holes *t* affording communication between said capillary channels and the central bore.

Just below its enlarged head, plug *n* is provided with an annular groove *u* and holes *v* connecting groove *u* and the central bore *s*. By screwing plug *n* inward, its head *o* recedes from the head of plug *m*, affording capacious channels, through groove *u*, holes *v* and bore *s* for discharge of the sludge from the bowl.

What I claim and desire to protect by Letters Patent is:

50. 1. In a centrifugal bowl, means operative during the normal operation of the bowl to discharge only one of two constituents of a mixture and also selectively operative to intermittently discharge the other constituent, said means comprising an annular outer member extending through the bowl wall, an inner member extending through the outer member, and having an orifice affording an opening for outflow of either constituent, means to throttle the inner opening to said orifice, there being a transverse channel through the inner member communicating with said orifice, the inner member being adjustable inward to provide a relatively unrestricted opening between the two members to provide an unrestricted passage from the interior of the bowl through said opening, channel and orifice to the exterior of the bowl, and means adapted to hold the inner member in its inwardly adjusted position against centrifugal force.
70. 2. In a centrifugal bowl, means operative during the normal operation of the bowl to discharge only one of two constituents of a mixture and also selectively operative to intermittently discharge the other constituent, said means comprising an

annular outer member extending through the bowl wall, a second inner member extending through the outer member and providing between said members an annular orifice through which either constituent may outflow to the exterior of the bowl, said inner member being manually adjustable inward relative to the outer member and, when not so adjusted, movable outward relative to the outer member under the influence of centrifugal force, said members having at their inner ends surfaces adapted, when said inner member is moved outward under the influence of centrifugal force, to substantially contact and when so contacted afford between them a passage of capillary character from the interior of the bowl to said annular orifice and adapted, when said inner member is manually adjusted inward, to be substantially separated and afford between them a free passage from the interior of the bowl to said annular orifice, and means on the two members adapted to cooperate to hold said inner member in its adjusted inward position to thereby hold said surfaces separated against the influence of centrifugal force.

3. In a centrifugal bowl, means operative during the normal operation of the bowl to discharge only one of two constituents of a mixture and also selectively operative to intermittently discharge the other constituent, said means comprising an annular outer member extending through the bowl wall, a second inner member extending through the outer member and providing between said members an annular orifice through which either constituent may outflow to the exterior of the bowl, said inner member being manually adjustable inward relative to the outer member and, when not so adjusted, movable outward relative to the outer member under the influence of centrifugal force, said members having at their inner ends surfaces adapted, when said inner member is moved outward under the influence of centrifugal force, to substantially contact and when so contacted afford between them a passage of capillary character from the interior of the bowl to said annular orifice and means, including a projection on one of said members and a groove in the other of said members, which, when the inner member is in its adjusted inward position, are adapted to cooperate to hold said inner member in its adjusted inward position to thereby hold said surfaces separated against the influence of centrifugal force and afford a free passage from the interior of the bowl to said annular orifice.

4. In a centrifugal bowl, means operative during the normal operation of the bowl to discharge only one of two constituents of a mixture and also selectively operative to intermittently discharge the other constituent, said means comprising an annular outer member extending through the bowl wall, an inner member extending through the outer member, means providing a passage affording an opening for the outflow of either constituent, means providing a throttled inlet to said passage, the inner member being manually adjustable inward to provide a relatively unrestricted opening from the interior of the bowl to and through said passage to the exterior of the bowl, and cooperating means on said two members to hold the inner member in its inwardly adjusted position against centrifugal force.

OLOF EINAR FRÖDING.
